WINDOW CONSTRUCTION

Richard B. Pollman, Detroit, Mich.

Application January 3, 1947, Serial No. 719,952

3 Claims. (Cl. 98—88)

1

This invention relates to building structures, and in particular to windows.

One object of this invention is to provide a window structure having standardized and interchangeable closure units fitting into the window openings of the building and consisting, as desired, of window pane units, ventilating units with or without screen units, and closure units to effectively seal off the ventilating units.

Another object is to provide a window structure of metallic construction so arranged that there is no direct metallic path of heat conduction between the outside and the inside of the window, this path being broken by insulating barriers so as to eliminate direct contact between the outside metal and the inside metal and thereby prevent one of the objections to the use of metallic window structures, namely their being too cold in winter and too hot in summer and wasteful either of heat in winter or of air conditioning refrigeration in summer.

Another object is to provide a window structure, as set forth in the preceding objects, wherein a filler unit is provided for enabling smaller units to be fitted into a larger window opening and thereby reduce the variety of units necessary to be manufactured as well as to make the various units more adaptable to different conditions and circumstances.

Another object is to provide a window structure wherein a ventilator unit, with or without a screen unit, is associated with a closure unit having a tight gasket seal so as to effectively prevent air leakage and the excessive linear foot crack loss previously occurring in conventional windows.

Another object is to provide a window structure, as set forth in the preceding objects, wherein the various units may be interchanged from top to bottom, whereby their order may be varied: for example, wherein a ventilator unit may be placed either at the top or at the bottom of the window opening or both, with a window pane unit in the central portion of the window opening or in the upper or lower portions thereof, as desired.

Another object is to provide a window structure, as set forth in the preceding objects, wherein in the window pane unit includes spaced double panes having improved means for sealing the air space between the panes against the entrance of moisture and other undesired influences.

Another object is to provide a window structure which will make the most effective use of double spaced pane window units by reducing heat losses to a minimum and by substantially eliminating undesired drafts by leakage through cracks.

2

Other objects and advantages of the invention will become apparent during the course of the following description of the accompanying drawings, wherein:

5 Figure 1 is an outside front elevation of a window structure according to the present invention, employing a single window pane unit filling the entire window opening of a building;

10 Figure 2 is an outside front elevation of a window structure utilizing the same window opening as in Figure 1, but employing a single window pane unit and a single ventilator unit;

15 Figure 3 is an outside front elevation of a window structure similar to Figures 1 and 2, but employing two ventilator units with a window pane unit between them;

20 Figure 4 is an enlarged vertical section through the window structure of Figure 2, showing the metallic framing construction and the means for preventing direct metallic contact between the outer and inner metallic frame members;

25 Figure 5 is an enlarged inside front elevation of the window structure shown in Figure 4 with a corner of the ventilator unit broken away, in section along the line 5—5 therein;

30 Figures 6 and 7 are perspective partly sectional views of the cooperating outer and inner metallic frame members of the window unit shown in both the upper and the upper middle portion of Figure 4;

35 Figures 8 and 9 are perspective partly sectional views of the cooperating outer and inner metallic frame members of the ventilator unit shown at the bottom of Figure 4;

Figures 10 and 11 are perspective partly sectional views of the cooperating outer and inner metallic frame members of the ventilator unit shown in the lower middle portion of Figure 4;

40 Figure 12 is an outside front elevation, partly in section, of a window structure showing the means of interconnecting the various window units;

45 Figure 13 is an enlarged fragmentary horizontal section taken along the line 13—13 in Figure 12, and showing further details of the means for interconnecting the window units; and

Figure 14 is an enlarged fragmentary vertical section of a modification of Figure 4, showing the use of a filler unit for spanning the space between the window opening and a window structure unit of the present invention which is smaller than the opening to be filled.

50 Referring to the drawings in detail, Figures 1 to 5 inclusive show window structures with interchangeable units according to a preferred form of the present invention and adapted to fit into a given size of window opening in a build-

ing (not shown) of conventional construction, and capable of being arranged in different combinations of such units. In particular, the interchangeable units shown in Figures 1 to 5 inclusive include units, generally designated as a large window unit 10 filling the entire window opening, a medium size window unit 11 combined with a ventilator unit 12 for filling the same window opening, and a small window unit 13 combined with two ventilator units 12 for filling the same window opening. It will be understood that the units 10, 11, 12 and 13 may be made of different, preferably standardized sizes for mounting in window openings of different sizes, as is found that the present invention enables the number of such units to be standardized and kept at a minimum for the number of window openings used.

The window units 10, 11 and 13, although differing in size, are of substantially the same construction and, for purposes of illustration, the medium-size window unit 11, as shown in Figures 2 and 4 will be described as exemplifying the construction also employed in the window units 10 and 13. The window unit 11 (Figures 2, 4 and 5) consists of top frame assemblies 14, bottom frame assemblies 15, and side frame assemblies 16. Since the side frame assemblies 16 are of similar construction to the top and bottom frame assemblies 14 and 15, as shown by turning Figure 13 on its side and comparing it with the central portion of Figure 4, a description of the assemblies 14 and 15 will suffice for all. The top and bottom frame assemblies 14 and 15 are also of similar construction except that they face in opposite directions. They consist of outer hollow frame members 17 and inner hollow frame members 18 with a hollow rigid insulating member 19 arranged between the members 17 and 18 to prevent direct metallic contact therebetween and thus to retard the conduction of heat therebetween. A retaining member 20 of L-shaped cross-section is also secured to the outer frame members 17 by fasteners 21 threaded into threaded holes 22 therein.

In detail, the outer frame member 17 consists of a forward vertical wall portion 23 facing outwardly and having a horizontal portion or first edge closure member 24 extending inwardly and separated therefrom by an angularly bent portion 25 providing a recess or groove 26 between it and the end portion 27 of the outer portion 23. The latter is also provided with an inclined portion 28 including the threaded holes 22 and terminating in a horizontal portion 29 substantially parallel to the horizontal portion 24, but of a shorter extent. The portions 28 and 29 together form a second closure member. The various portions 23, 24, 25, 28, and 29 are engaged by correspondingly configured portions 30, 31, 32, 33 and 34 respectively of the rigid insulating member 19, which likewise is provided at its ends with bent portions 35 and 36 extending into the gaps between the inner ends 37 and 38 of the horizontal portions 24 and 29 and the adjacent portions of the inner frame member 18 so as to insulate these from direct metallic contact with one another.

The inner frame member 18 is provided with an inner vertical wall portion 39 having an end portion 40 and an angularly bent portion 41 providing a recess or groove 42 corresponding to the similar recess or groove 26. The inner frame member 18 is also provided with a horizontal portion or third edge closure member 43 which in turn is connected to an internal vertical wall portion or partition 44, the upper end 45 of which en-

gages the portion 31 of the rigid insulating member 19. The inner frame member 18 is finally provided with an offset vertically extending portion 46 terminating in a horizontally bent portion 47 for window-pane retaining purposes, as set forth below. The outer and inner frame members 17 and 18 and the rigid insulating member 19 cooperate to enclose chambers 48 and 49 respectively for receiving insulating material 50, such as fibrous material of a conventional type well known in the building industry. Portions of the material itself have been omitted from the drawings in order to avoid unduly complicating the showing thereof and conflicting with the showing of the other parts of the structure. Such insulating material, for example, may consist of glass fibre, rock wool, cork or other well-known and conventional insulation.

Mounted in the space between the portions 43 and held between the angle members 20 and the portions 46 and 47 of the inner frame member 18 are window-setting members 51 (Figure 4) of mastic or other suitable material, having spaced grooves 52 therein for the reception of spaced window panes 53 and 54. The grooves 52 are filled out by locking members 55 of approximately U-shaped cross-section with their free ends entering the grooves 52 and engaging the adjacent surfaces of the window panes 53 and 54 so as to hold the window panes firmly in the grooves 52. The window pane assembly 56 consisting of the panes 53 and 54, the window-setting members 51 and the locking members 55 is inserted by removing the fasteners 21 and angle members 20, whereupon the window pane assembly 56 is slid into the space between the portions 43 of the inner frame members 18 until the bent-over portions 47 engage the inner surface of the inner pane 53 (Figure 4). The angle members 20 are then replaced in abutment with the window setting members 51 and the fasteners 21 again screwed into the holes 22, securing the window pane assembly 56 in position. To connect the window unit 11 to adjacent units, the portions 44 of the inner frame members 18 are provided with inwardly extending bosses 57 having vertical holes 58 aligned with corresponding holes 59 and 60 in the portions 28 and 24 respectively.

Passing through the holes 58, 59 and 60 are bolts 61 which likewise pass through holes 62 and 63 in the opposite parallel portions 64 and 65 extending horizontally from vertical portions 67 of outer frame members 66 of the louver units 12 (Figures 4 and 10). The frame members 66 are provided with vertically extending ribs 68 mating with the grooves 26 and hence correspondingly configured. Direct metallic contact between the portions 24 and 64 is prevented by the insertion of a plate-like rigid insulating member 69 therebetween, the inner end of which passes along and engages the upper surface of an inner frame member 70 (Figures 4 and 11) having a substantially horizontal intermediate portion 71 of approximately wedge-shaped cross-section with a vertically extending rib 72 fitting into and mating with the groove 42 of the inner frame member 18 so as to interlock these members. The opposite end of the inner frame member 70 is provided with an oppositely extending vertical rib 73 forming an abutment for engagement by a gasket 74 of elastic deformable material such as rubber, synthetic rubber or the like. The inner frame members 70 are provided with vertically extending bosses 75 with vertical holes 16

through which the bolts 61 pass (Figures 4 and 11).

The outer and inner side frame members 77 and 78 respectively are similar in construction and configuration to the outer and inner frame members 66 and 70, hence require no further description. Arranged between the opposed side frame members 77 are inclined louvers 79 having bent opposite edges 80 and 81 (Figure 4) to prevent the direct passage of air through the spaces between the louvers 79. In the space between the vertical portions 81 of the louvers 79 and the inner side members 78 and frame members 70 is mounted a screen unit 82 consisting of a frame 83 of U-shaped cross-section (Figure 4) having the free edges of the screen portion 84 inserted between the arms of the frame 83 and locked therein by forcing these together.

The screen frame 83 also engages the horizontal portion 85 of a horizontal outer louver frame member 66 (Figures 4 and 8) having an inclined portion 87 connecting the horizontal portion 85 with the vertical portion 88 with a vertically extending rib 89 corresponding to the bent portions 81 of the louvers 79. The outer louver frame members 83 are also provided with horizontal portions 90 extending inwardly from the vertical portions 88 and provided with ribs 91 spaced apart from the free edge 92 of the vertical portion 88 and forming the side walls of a groove 93 similar in form and purpose to the grooves 26. The horizontal portions 85 and 90 are provided with aligned holes 94 and 95 for the reception of bolts 96 which likewise pass through vertical holes 97 in bosses 98 formed on the vertical partition portions 99 of inner louver frame members 100 (Figures 4 and 9). The inner louver frame members 100 are provided with inclined portions 101 and outer vertical portions 102, the latter terminating in offset ribs 103 forming elongated recesses or notches 104 of L-shaped cross-section.

In order to prevent direct metallic contact between the outer and inner louver frame members 66 and 70, a rigid insulating member 105 is provided (Figure 4) having spaced horizontal portions 106 and 107 interconnected by vertical portions 108, the horizontal portion 106 terminating in a vertical portion 109 which enters the gap between the horizontal portion 64 of the outer frame members 66 and the outer surface of the inner louver frame member 70. Similarly, the louver frame members 86 and 100 are provided with a rigid insulating member 110 having a horizontal portion 111, an inclined portion 112, a vertical portion 113 and an extended horizontal portion 114 passing between the partition 99 and the horizontal portion 90 and terminating in a bent portion 115 entering the gap between the outer and inner louver frame members 86 and 100, so as to prevent direct heat conduction therebetween. The chambers 116, 117 and 118 lying within the rigid insulating members 105 and 110 and within the inner louver frame member 100 respectively, are filled with fibrous or other suitable conventional insulating material 50 in the same manner as the chambers 48 and 49 previously described.

Fitting into the inclined walled aperture formed by the inner louver frame members 10, 78 and 100 and engaging the gasket 74 is a removable closure unit 120 (Figure 4) having plate-like front and rear walls 121 and 122 and inclined side walls 123 terminating in vertically extending flanges 124 having rigid insulating

members 125 associated therewith. The upper edge of the closure unit 120 is provided with a vertically extending flange 126 abutting the portion 72 of the inner louver frame member 70.

Figures 12 and 13 illustrate how adjacent window units 11 are joined together when they are placed side by side in the same building opening so that several such units are employed to fill a single building opening. By turning Figure 13 upon its side and comparing it with the central portion of Figure 4, it will be seen that the side frame members 16 are similar in construction to the horizontal frame members 17 and 18 and parts similar to those previously described are similarly designated. To interconnect adjacent side frame members 16 of window units 11 (Figure 13), the bolts 61 passing through the bosses 57 are provided as before, except that these likewise pass through holes 127 in spacing members 128 (Figure 12). A rigid insulating structure 129 of hollow rectangular cross-section is provided to fill the space between the adjacent portions 24 of the frame members 16 and this may likewise be filled with suitable insulating material 50, preferably of a fibrous nature. The gaps between the adjacent edge flanges or ridges 27 and 40 are filled by elongated hollow cover strips 130 (Figure 13) of approximately T-shaped cross-section and having inwardly extending wings or ribs 131 entering the gap and bent over as at 132 to form portions entering the grooves 26 and 42 respectively. In practice, the cover strips 130 are sprung into the gaps between the ridges 27 and 40 and the portions 132 snap into the grooves 26 and 42 therebeyond.

The modification shown in Figure 14 provides a filler unit 135 to fill out the space between a unit, such as a ventilator unit 12 and the building opening where the unit 12 itself is insufficient to fill the space along with its window unit 10 or 13. The filler unit 135 consists of hollow outer and inner frame members 136 and 137 respectively having rigid insulating members 138 and 139 to prevent direct metallic contact between them or between either of them and the adjacent ventilator unit 12 or window unit 10, 11 or 13. The outer frame member 135 is provided with a vertical wall 140 having lower and upper grooves 141 and 142 and narrow and wide horizontal portions 143 and 144 respectively. The inner frame member 137 similarly consists of a vertical portion 145 with a horizontal portion 146 continuing in a partition portion 147 which engages the free ends of the rigid insulating member 138. The portion 145 is also provided with a groove 148, the grooves 141 and 148 serving to receive the ribs 68 and 72 on the ventilator unit 12. The frame members 136 and 137, in cooperation with the rigid insulating member 138 enclose chambers 149 and 150 which are filled with insulating material 50, preferably of a fibrous nature as previously described herein. While the filler unit 135 has been described and illustrated in connection with a ventilator unit 12, it will be evident that it can be used also in connection with the window units 10, 11 and 13.

For ornamental purposes, in certain types of buildings, such as residences of the so-called Georgian or Cape Cod cottage type, the attractiveness of the building is enhanced by the use of multiple small panes in each window opening. Such small panes are, however, difficult to clean as compared with a single large pane.

The present invention also solves this problem by employing large panes 53 and 54 (Figure 4) but obtains the effect of small panes by providing an insertable and removable grille unit 151 consisting of a marginal frame member 152 fitting into the space between the inclined outer frame portions 28 and having cross bars 153 forming a lattice-work simulating the mullions into which small window panes are customarily fitted. To clean the outside of the single large window pane 54, it is merely necessary to remove the grille unit 151, replacing it after the cleaning has been accomplished.

The assembly of the various units into a window opening in a building is self-evident and follows from the foregoing description of the construction of these units. A large window unit 10 may be used alone in an opening or assembled side by side with other units in a large opening as shown in Figure 12, by means of the spacing members 128 and cover strips 130 shown in Figure 13. Optionally, a louver unit 12 may be combined with a medium-size window unit 11 (Figures 2, 4 and 5), or two louver units 12 may be combined with a small window unit 13 (Figure 3) in the manner previously described. Where a louver unit 12 is insufficient to fill the space, the filler unit 135 is inserted and spans the gap between the louver unit 12 and the building opening as shown in Figure 14. Adjacent window units 10, 11 or 13 and louver units 12 may be joined together in a single building opening by the use of the spacing members 128 and the elongated cover strips 130 as shown in Figures 12 and 13.

In wintertime, the louver units 12 are sealed by the closure units 120 (Figures 4 and 5) which tightly engage the gasket 14 and prevent leakage of air by lineal foot crack loss. The various units may be quickly assembled from standardized units prefabricated in a factory and a wide variety of units is thus afforded.

While I have shown and described my invention in detail, it is to be understood that the same is to be limited only by the appended claims, for many changes may be made without departing from the spirit and scope of my invention.

What I claim is:

1. A building structure for mounting in a building opening comprising a window unit having an open centered frame structure with a window pane mounted therein, and a ventilating unit disposed in said building opening independently of and separable from said window unit and having an open centered frame structure with spaced ventilating louvers mounted therein, said window and ventilating units being mounted in edge to edge abutting relationship in said building opening and having interengaging portions mating with one another in freely-separable interfitting relationship along said abutting edges, each frame structure being of hollow construction with a chamber extending substantially around the entire periphery of the window pane and heat insulating material disposed in said chamber.

2. A building structure for mounting in a building opening comprising a window unit having an open centered frame structure with a window pane mounted therein, and a ventilating unit disposed in said building opening independently of and separable from said window unit and having an open centered frame structure with spaced ventilating louvers mounted therein, said window and ventilating units being

mounted in edge to edge abutting relationship in said building opening and having interengaging portions mating with one another in freely-separable interfitting relationship along said abutting edges, each of said frame structures being composed of laterally spaced outer and inner frame members and edge closure members engaging and extending between the edges of said outer and inner frame members to enclose a chamber extending substantially around the entire periphery of said window pane, a partition member disposed between said outer and inner members and dividing said chamber into outer and inner portions, and heat insulating material of relatively low heat conductivity disposed in said outer and inner portions of said chamber, said partition member being connected to one of said frame members.

3. A building structure for mounting in a building opening comprising a window unit having an open centered frame structure with a window pane mounted therein, a ventilating unit disposed in said building opening independently of and separable from said window unit and having an open centered frame structure with spaced ventilating louvers mounted therein, said window and ventilating units being mounted in edge to edge abutting relationship in said building opening and having interengaging portions mating with one another in freely-separable interfitting relationship along said abutting edges, said frame structures being of hollow construction with cavities therein and having heat insulating material disposed in said cavities, said units having a combined length less than the length of said building opening with a gap therebetween, and a filler unit mounted in said gap in edge to edge abutting relationship with one of the other units in said building opening, said filler unit and said other unit having interengaging portions mating with and freely separable from one another in interfitting engagement along the abutting edge, said filler unit having spaced outer and inner walls and spaced upper and lower walls secured to and interconnecting said outer and inner walls, said upper and lower walls and said outer and inner walls enclosing a filler chamber, and heat insulating material disposed in said filler chamber.
